By Higdon & Longan,

Attest,

UNITED STATES PATENT OFFICE.

LEOPOLD KABIS, OF CHEYENNE, WYOMING, ADMINISTRATOR OF THOMAS MOORE, DECEASED.

DESIGN FOR A BUCKLE.

SPECIFICATION forming part of Design No. 29,277, dated August 30, 1898.

Application filed July 27, 1898. Serial No. 687,042. Term of patent 14 years.

To all whom it may concern:

Be it known that THOMAS MOORE, deceased, late a citizen of the United States, and a resident of Cheyenne, county of Laramee and State of Wyoming, duly invented and produced a new and original Design for a Buckle, of which the following is a full, clear, and exact description, reference being had to the accompanying drawing, forming a part thereof.

The figure is a plan view of a buckle embodying the design.

As shown in the drawing, the leading or material feature of the design consists of a rectangular loop 1, the lower horizontal bar 2 of which is slightly larger in diameter than is the balance of said loop, and from the lower

corners of said loop 1 extends downwardly an elongated oval loop 3. The loop 2 is in direct alinement with the loop 1, and the space between the rounded ends of said loop 3 is considerably greater than is the space between the ends of the rectangular loop 1.

What is claimed is—

The design for a buckle, substantially as herein shown and described.

In testimony whereof I affix my signature in presence of two witnesses.

LEOPOLD KABIS,
Administrator of Thomas Moore, deceased.

Witnesses:

WALTER R. STOLL,
WM. R. SCHNITGER.
